SNOW PLOW

William A. McNulty, Chicago, Ill.

Application October 13, 1936, Serial No. 105,374

2 Claims. (Cl. 37—36)

This invention relates to snow plows and more particularly to snow plows adapted for use with railway equipment.

In removing snow from a railway right of way 5 it is desirable to remove the snow from between the rails and this may be done by causing the flanger blades of a snow plow to pass between the rails, but because of track intersections, switches and the like it is essential that the flanger plates 10 and the blades thereon be capable of being retracted from between the rails when approaching track intersections and switches and the like so as to prevent the flangers from jamming on the rails intersecting those between which they are 15 operating, and therefore one of the objects of my invention is to provide a novel snow plow wherein the flangers may be operated between the rails but which may be retracted from between the rails to clear intersecting rails, switches and the like.

It is desirable to remove snow as close as possible to the road bed but at the same time the flanger blades must be kept free from the ties and the like of the road bed and hence another 20 object of my invention is to provide a snow plow wherein the flangers may be lowered into a definite position relative to the road bed so that substantially all of the snow between the rails may be removed without the flangers striking the ties 25 or the like of the road bed.

Another object of my invention is to prevent derailing of the locomotive or the like to which my snow plow is attached if the flangers strike an obstruction on the road bed.

Heretofore it has been proposed to provide devices for raising and lowering the flangers of a snow plow associated with a locomotive or the like and it has been proposed to bring this about by pressure operated means, but heretofore such pressure operated means have been located in such a position that snow dug up by the plow could contact therewith and this impaired proper operation of the pressure operated means, and hence another object of my invention is to employ pressure operated means to elevate and lower the flangers of a snow plow from and to operative position and to so position such pressure operated means that snow dug up by the plow is prevented from contacting therewith and impairing operation thereof.

It is not only desirable to remove snow from between the rails of a railway right of way but also to spread snow so removed well away from the right of way, and a further object of my invention is to spread snow removed by a plow well

beyond the sides of the rails of the right of way, and an object ancillary to the foregoing is to associate wings with the flangers of the plow so that snow removed by the flangers will pass onto the wings to be dispersed well to the side of the rails of the right of way, and a still further object is to so arrange the wings that they will be retracted from or advanced into operating positions along with the movement of the flangers of the plow into and from operative position, and an object ancillary to this is to move the wings into and to maintain the wings in operative position by pressure operated means also located to prevent snow removed by the plow from impairing proper operation thereof.

Still further objects of the invention are to elevate and maintain elevated the flangers of a snow plow by pressure operated means whereby the flangers will be supported for movement relative to the road bed and other parts of the plow when in operative position; to interconnect the flangers and wings of my improved snow plow and thereby enable the flangers and wings to be synchronously moved into and from operative position; to provide a snow plow which may be expeditiously attached or removed from a locomotive or other railway equipment; and to provide a novel snow plow of simple and economical construction and efficient and positive operation.

A selected embodiment of my invention is illustrated in the accompanying drawings wherein

Fig. 1 is a side elevational view in which my novel snow plow is shown mounted on a fragmentally illustrated locomotive;

Fig. 2 is a top plan view of my novel snow plow;

Fig. 3 is a rear elevational view;

Fig. 4 is a sectional view taken substantially on the line 4—4 on Fig. 3; and

Fig. 5 is a detail view similar to Fig. 1 showing another means for operating my novel snow plow.

My novel snow plow is preferably substituted for the usual pilot of a locomotive or the like and to this end the pilot is removed and my novel snow plow is fastened to those portions of the locomotive or the like to which the pilot is usually attached. In this way I am enabled to attach my novel plow to the locomotive without having portions of the plow projecting into the path of the snow being removed from the right of way by my plow whereby dispersion of the snow well to the sides of the railway right of way is not impaired by parts of the plow. To this end my novel plow includes a transverse beam 10 which may be bolted or otherwise suitably secured to the frame of the locomotive in the position where

the usual pilot beam of the locomotive is secured. The beam 10 is arranged at the rear end of my plow and at the forward end thereof a carrier beam 11 is provided and these beams are interconnected adjacent their ends to side beams 12 and 13. Reinforcing beams 14 and 15 are provided intermediate the side beams to extend parallel to the side beams between the carrier and rear beams 11 and 10 whereby a rigid frame is provided.

As best shown in Fig. 4, the forward ends of the beams 12, 13, 14 and 15 are bent to provide downwardly extending legs 16, 17, 18 and 19, respectively, and the lower ends of these legs are bent rearwardly to provide foot portions or stops 20, 21, 22 and 23. The legs 16, 17, 18 and 19 do not extend at right angles to the main extent of the beams 12, 13, 14 and 15 but are inclined as shown in Fig. 4 for a purpose to be explained. As best shown in Fig. 2, the forward ends of the beams 14 and 15 are arranged forwardly of the forward ends of the beams 12 and 13, the purpose of which will also be explained.

A pair of flanger plates 24 and 25 are provided which are adapted to be arranged in side by side relation, the plate 24 being rested on the forward faces of the legs 16 and 17 and the plate 25 being rested on the forward faces of the legs 18 and 19. Inasmuch as the leg 18 is forwardly of the leg 16 and the leg 19 is forwardly of the leg 17 the flanger plates 24 and 25 are disposed in angular relation with respect to each other when these plates are rested on the front faces of the legs and the apex defined by the angular relation of these plates is located substantially medially of the plow. The upper edges of the flanger plates 24 and 25 are rolled to provide deflectors 26 and 27, the purpose of which is explained hereinafter.

A pair of angle brackets 28 and 29 are arranged in side by side relation to extend upwardly from the lower edge of the flanger plate 24 adjacent the inner edge thereof. These brackets are disposed on the rear face of the flanger plate 24 and are spaced apart sufficiently to receive the leg 18 therebetween. The angle brackets 28 and 29 are securely fastened to the flanger plate 24 by rivets or the like. Another pair of angle brackets 30 and 31 are similarly positioned on the flanger plate 25 and receive therebetween the leg 19.

As best shown in Fig. 4, the width of the parallel portions of the angle brackets 30 and 31 is of greater extent than the thickness of the leg 19 and bolts 33 and 34 extend between the parallel portions of the brackets 30 and 31 rearwardly of the rear face of the leg 19. These bolts respectively pass through sleeves 35 and 36 that are disposed between the parallel portions of the brackets 30 and 31 and which bear on the rear face of the leg 19. It will thus be seen that the flanger plate 25 is connected to the leg 19 for movement therealong but is held against displacement therefrom. In a manner similar to this the flanger plate 24 is connected to the leg 18 through the angle brackets 28 and 29. Furthermore, similar pairs of angle brackets are provided adjacent the outer edges of the flanger plates 24 and 25 and through these angle brackets the plates 24 and 25 are connected to the legs 16 and 17 in the just described manner.

Thus the flanger plate 24 is mounted for substantially vertical movement along the legs 16 and 18 and the flanger plate 25 is mounted for substantially vertical movement along the legs

17 and 19. The sleeves as 36 are adapted to engage the stops as 23 to limit downward movement of the flanger plates as 25 and when the sleeves as 36 engage the stops as 23 the flanger plates are disposed in predetermined relation with the road bed.

The rails R and R' are mounted on ties T and as the locomotive or the like to which my novel plow is attached travels along the rails R and R' the flanger plates are adapted to remove snow from between these rails. Inasmuch as wear will be greatest at the lower leading edges of the flanger plates 24 and 25 flanger blades 37 and 38 are detachably connected at the lower leading edges of the flanger plates. By reason of the removable mounting of these flanger blades they may be removed and replaced when they become worn. A recess 39 is provided in the flanger blade 37 and a recess 40 is provided in the flanger blade 38. The rails R and R' respectively pass into these recesses when the flanger plates 24 and 25 are lowered and the sleeves as 36 rest on the stops as 23. When the sleeves as 36 rest on the stops as 23 the inner edges of the notches 39 and 40 just clear the top of the rail and the portions of the flanger blades 37 and 38 intermediate these recesses are disposed between the rails and act to remove substantially all the snow from between the rails R and R' without coming in contact with the ties T or the like between the rails. Inasmuch as the stops 23 are rigid it will be apparent that the flanger blades of the flanger plates are accurately positioned thereby relative to the surface of the road bed, and this prevents injury to both the blades and the road bed which would probably result if the blades could contact with the road bed.

It has been explained that it is desirable that the flanger blades be arranged so that they can be elevated and lowered so that when rails intersecting the rails R and R' are approached or when a switch is approached the flanger blades 37 and 38 may be retracted from between the rails and thereby be prevented from striking such intersecting rails or the like. To this end the lower ends of chains 41 and 42 are connected to the rear face of the flanger plate 24 and similarly chains 43 and 44 are connected to the rear face of the flanger plate 25. The upper ends of the chains 41 and 42 are bolted or otherwise suitably secured to the outer free end of an arm 45 and the upper ends of the chains 43 and 44 are similarly connected to the outer free end of the arm 46. The rear ends of the arms 45 and 46 are fast to a rock shaft 47 mounted in brackets 48 and 49 extending upwardly from the carrier beam 11.

An arm 78 extends upwardly from the rock shaft 47 adjacent the bracket 48 and the free end of this arm 78 is disposed in a bifurcation in one end of the arm 79, said arms being pivotally interconnected by a bolt or rivet 80 or the like. The other end of the arm 79 is connected to the piston rod 82 of the piston in the cylinder 81 which is mounted on the running board of the locomotive well rearwardly of the rear beam 10 of my novel snow plow. When steam or air under pressure is admitted into the cylinder 81 in front of the piston therein this piston is forced rearwardly and this rearward movement is transmitted through piston rod 82 and arm 79 to the arm 78 whereupon the rock shaft 47 is rotated to move the arms 45 and 46 upwardly and this, through the chains 41 and 42 and 43 and 44, elevates the flangers 24 and 25.

into their upper or inoperative position. When pressure is applied in the back of the piston in the cylinder 81 the piston rod 82 and arm 44 are moved forwardly whereupon the rock shaft 5 47 is rotated to lower the arms 44 and 45. This movement of the arms 44 and 45 is sufficient to free the chains of tension and the flangers drop down and rest upon the foot portions 20, 21, 22 and 23 and are free to move on the legs 10 16, 17, 18 and 19.

It has been explained that it is desirable that snow removed from the road bed of a railway right of way be dispersed well to the sides of the road bed. This can be effectively accomplished 15 by positioning wings adjacent the outer free edges of the flanger plates 24 and 25 in such location that snow picked up by the flanger plates 24 and 25 and moved up over the front surface thereof to the deflectors 26 and 27 thereon will pass 20 onto the wings to be spread well to the sides of the right of way. To this end brackets 62 and 63 depend downwardly from the side beams 12 and 13 adjacent the forward ends thereof and provide foot portions 64 and 65 in which the lower 25 ends of bars 66 and 67 are rockably mounted. The brackets 48 and 49 include portions which project beyond the side edges of the side beams 12 and 13 and the circular portions 68 and 69 on the shafts 66 and 67 are mounted therein, said 30 shafts including portions 66' and 67' that extend above the brackets 48 and 49. The inner edges of wings 70 and 71 are secured to the bars 66 and 67 and are movable with the bars to and from operative position.

35 A bracket 82 extends between the carrier beam 11 and the bracket 63 and a reenforcing bar 83 extends between a depending boss 84 on the side beam 13 and said bracket 63. The brackets 82 and 83 serve to reinforce the bracket 63 and similar brackets are associated with the bracket 62.

The wings are adapted to be held in their outer operative position to receive snow from the flangers 24 and 25 and the deflectors 26 and 27 thereon. Furthermore the wings are to move 45 into this outer operative position when the flangers are lowered to rest on the foot portions as 20.

Hence another rock shaft 53 is provided and it is mounted in brackets 54 and 55 carried by the side beams 12 and 13 respectively. An arm 56 50 depends downwardly from the rock shaft 53 into a bifurcation at one end of the arm 51 and the arms 56 and 51 are pivotally interconnected by a bolt 57 or the like. An arm 58 extends upwardly from the rock shaft 47 and the adjacent end of 55 the arm 51 is pivotally connected thereto by a bolt 52 or the like. Thus through the arm 51 the rock shafts 53 and 47 are interconnected.

An inwardly extending arm 72 is secured at the upper end of the portion 66' and another inwardly extending arm 73 is secured at the upper end 60 of the portion 67. An upwardly extending arm 74 is fast on the rock shaft 53 and the arms 72 and 74 are interconnected by a link 75. Another arm 76 extends upwardly from the rock shaft 53 and a link 77 interconnects the free end 65 of this arm with the free end of arm 73. In this manner the bars 66 and 67 are connected to the rock shaft 53.

Therefore whenever the rock shaft 47 is rotated to lower the arms 45 and 46 which results in movement of the flangers 24 and 25 into operative position this movement is transmitted through the arm 51 to the rock shaft 53 and thence through the arms 74 and 76, links 75 and 76 77 and arms 72 and 73 to the bars 66 and 67

whereupon the wings 70 and 71 are moved into their outer operative position. Contrariwise when the rock shaft 47 is rotated to elevate the flangers 24 and 25 the wings are retracted into their inner or inoperative position.

5

While the wings 70 and 71 will be moved into their outer operative position upon lowering of the flangers 24 and 25 the pressure exerted thereon by snow passing thereover might be sufficient to force these wings inwardly. Hence 10 these wings are effectively held in their outer operative position and to this end an upwardly extending arm 58 is provided on the rock shaft 53 and one end of a link 59 is pivotally connected to the free end of arm 58. The other end of the 15 link 59 is pivotally connected to the piston rod 61 of the piston in the cylinder 60 mounted on the locomotive adjacent the cylinder 81.

When air under pressure is admitted in front of the piston in the cylinder 60 the piston rod 61 20 is moved rearwardly and this, through the link 59, so moves the rock shaft 53 that the wings 70 and 71 are forced into and held in their outer operative position. Furthermore when air is applied in back of the piston in the cylinder 60 the 25 wings are retracted into their inner inoperative position.

Inasmuch as the rock shafts 47 and 53 are interconnected and as each is connected to a pressure operated means, the cylinders 60 and 30 81, it is advantageous to operate the pressure operated means simultaneously. Furthermore, the pistons in the pressure operated means are adapted to move in opposite directions in such simultaneous operation thereof. Hence I provide a valve V and I extend a pipe 85 from one port in this valve to the front end of the cylinder 81 and I extend a pipe 86 from a cooperating port in the valve to the rear end of the cylinder 60. I also extend a pipe 87 from another port in 40 the valve to the front end of the cylinder 60 and from a cooperating port in the valve I extend a pipe 88 to the rear end of the cylinder 81. A supply pipe 89 leads from the valve V to a source of supply of steam or air under pressure. The 45 valve V is of the type which may be moved into a position so as to shut off flow to all of the ports or into a position such that flow may be through the pipes 85 and 86 or into another position where the flow will be through the pipes 50 87 and 88.

In an arrangement wherein a device such as the valve V is provided when it is desirable to render my plow operative the valve is positioned to admit pressure into the cylinder 81 through 55 the pipe 89 and into the cylinder 60 through the pipe 87 whereupon the pistons in these cylinders and the piston rods move in the manner similarly described to dispose the flangers and the wings in their operative position. When the flangers 60 or wings are to be moved into their inoperative position the valve is positioned to cause flow through the pipes 85 and 86 whereupon the pistons in the cylinders 59 and 60 are moved in the manner previously described. It will thus be 65 seen that the provision of a valve such as the valve V facilitates the operation of my novel snow plow.

Another equally efficient means for operating my snow plow is illustrated in Fig. 5 wherein the 70 cylinders 60a and 81a have only one source of steam or air supply thereto through the pipes 86a and 88a respectively. The steam or air is admitted to the pipes 86a and 88a by means of a valve Va which controls the pressure from the 75

source of supply fed to the valve V_a through the pipe $89a$. The piston in the cylinder $60a$ has an angular piston rod $61a$ extending through the end wall of the cylinder and connected to the link 59 . A coil spring 90 is mounted on the piston rod within the cylinder and when the pressure is released by the valve V_a the spring forces the piston to the right, Fig. 5. The opening in the end of the cylinder through which the piston rod passes is larger than the rod, permitting free movement of air in back of the piston into and out of the cylinder as the piston moves back and forth. The cylinder $81a$ is constructed similar to the cylinder $60a$ and is provided with a spring 91 about the piston rod $82a$ within the cylinder.

As the valve V_a is operated to admit pressure into the cylinder $60a$ the same valve connects the cylinder $81a$ to the atmosphere through the pipe $88a$. Therefore the flangers 24 and 25 are lowered and the wings 70 and 71 are forced into and held by the continued pressure in cylinder $60a$ in their outer operative position simultaneously. As pressure is admitted to the cylinder $81a$ by means of the valve V_a and pipe $88a$ the cylinder $60a$ is connected to the atmosphere through the pipe $86a$ and the flangers are raised and held in raised position by the continued pressure in cylinder $81a$ and the wings are folded inwardly to their inoperative position simultaneously. The structure disclosed in Fig. 5 for operating the snow plow provides simple structure and an equally as efficient structure as the means shown in Fig. 1 for operating the snow plow.

From the foregoing description it will be apparent that I have provided a snow plow which will act to remove snow from between the rails of a railway right of way and one which may be easily elevated out of such operative position when intersecting rails, switches or the like are approached. Furthermore, those portions which will be subjected to the greatest wear are arranged so that they can easily be replaced. In addition to the foregoing wings are provided which are moved to and from an operative position when the flangers of my plow are moved to and from operative position, and these wings serve to spread the snow well to the sides of the right of way. The means for moving the wings to and from operative position may be arranged for adjustment so that the wings may be moved into different positions relative to the flangers which will control the amount to which snow is spread to the sides of the right of way.

Another very important feature of my invention is the manner in which the legs supporting the flangers are arranged. These legs are of sufficient strength to resist the force which will be impressed thereon by reason of the plowing action, but if an obstruction is encountered these legs will bend rearwardly and so fold under that derailing of the locomotive is prevented. This is also prevented by the manner in which the flangers are supported in operative position, that is to say, the supporting of the flangers for free movement on the supporting legs therefor away from the stops which dispose the flangers in proper operative position.

While I have illustrated and described a se-

lected embodiment of my invention it is to be understood that this is capable of variation and modification and I therefore do not wish to be limited to the precise details set forth but desire to avail myself of such changes and alterations as fall within the purview of the following claims.

I claim:

1. A snow plow comprising a guiding and supporting frame, a pair of flanger blades slidably mounted upon the said guiding and supporting frame and slidably guided thereby for movement into lowered or effective position and into raised or ineffective position, a pair of wings pivotally mounted upon the said guiding and supporting frame, one adjacent the outer end of each of the said flanger blades, for movement into extended or effective position and into folded or ineffective position, relative to the said flanger blades, and means for simultaneously moving both of the said flanger blades and both of the said wings into and out of their effective positions, said means including a rock shaft extending horizontally across the said frame rearwardly of the said flanger blades, a pair of horizontally spaced arms carried by the said rock shaft and extending forwardly from the said rock shaft above the said flanger blades, a pair of flexible elements each attached to one of the said arms and each attached to one of the said flanger blades, a second rock shaft extending horizontally across the said guiding and supporting frame rearwardly of and parallel to the said first-named rock shaft, means operatively interconnecting the said rock shafts, means operatively interconnecting each of the said wings to the said second-named rock shaft, and means for rocking the said shafts.

2. A snow plow comprising a guiding and supporting frame, a pair of flanger blades slidably mounted upon the said guiding and supporting frame and slidably guided thereby for movement into lowered or effective position and into raised or ineffective position, a pair of wings pivotally mounted upon the said guiding and supporting frame, one adjacent the outer end of each of the said flanger blades, for movement into extended or effective position and into folded or ineffective position, relative to the said flanger blades, and means for simultaneously moving both of the said flanger blades and both of the said wings into and out of their effective positions, said means including a rock shaft extending horizontally across the said frame rearwardly of the said flanger blades, a pair of horizontally spaced arms carried by the said rock shaft and extending forwardly from the said rock shaft above the said flanger blades, a pair of flexible elements each attached to one of the said arms and each attached to one of the said flanger blades, a second rock shaft extending horizontally across the said guiding and supporting frame rearwardly of and parallel to the said first-named rock shaft, a link mechanism operatively interconnecting the said rock shafts, a link mechanism operatively interconnecting each of the said wings to the said second-named rock shaft, and means, including fluid-pressure operated pistons for rocking the said shafts.
